UNITED STATES PATENT OFFICE

ROSWELL A. MOORE, OF WATERBURY, CONNECTICUT, ASSIGNOR TO GEORGE FROST COMPANY, OF BOSTON, MASSACHUSETTS.

GARTER.

1,406,995.

Specification of Letters Patent. Patented Feb. 21, 1922.

Application filed June 3, 1921. Serial No. 474,601.

To all whom it may concern:

Be it known that I, ROSWELL A. MOORE, a citizen of the United States, residing in Waterbury, in the county of New Haven and 5 State of Connecticut, have invented certain new and useful Improvements in Garters, of which the following is a specification.

This invention relates to gentlemen's garters of the kind commonly called "pad" 10 garters in which the stocking-engaging clasp members are connected with the leg-band by a clasp-suspending device secured to a pad arranged between the ends of the leg-band.

In such garters one end of the leg-band 15 is permanently secured to one side of the pad while the other end of the band is detachably connected therewith by a hook-and-eye fastening, the eye being attached to a tab projecting from the pad and the hook being 20 connected with a loop in the band provided with a sliding take-up device by means of which the length of the leg-band may be adjusted.

The object of my invention is to provide 25 means for connecting the eye member of the fastening to the pad in such manner that it is not apt to slip and may be held in place without stitching. My invention is particularly applicable to garters in which the leg- 30 band is made wider than those commonly employed.

According to my invention I provide a new form of eye which may be connected with the pad without being stitched thereto 35 and yet without danger of slipping out of place.

My improvements are illustrated in the accompanying drawings, in which—

Figure 1 is a perspective view of a pad 40 garter with my improvements applied.

Figure 2 is a view on an enlarged scale, illustrating the manner in which the eye member is applied.

Figure 3 shows a section on the line 3—3 45 of Fig. 2 and illustrates how the fabric of the tab is connected with the eye.

Figure 4 is a perspective view of the improved eye.

In the drawings A indicates the pad, B 50 the leg-band and C a stocking-engaging member or clasp suspended from the pad. One end of the leg-band is permanently connected with the pad at a in the usual way.

The opposite end of the band is looped, as 55 indicated at b, and provided with a slide

A hook member F is connected with the loop b and is adapted to engage the eye member G. This eye member is attached to a fabric tab H stitched to the pad A, in the 60 manner indicated in Fig. 3. This tab is in the form of a loop, as shown most clearly in Fig. 3.

The eye member G comprises a frame consisting of relatively long frame bars g, g' 65 and relatively short end bars g², g³ which are connected by a cross-piece L formed mid-way between its opposite ends with an eye l. The frame bar g is formed with a series of teeth x which project laterally from 70 the outside thereof. It will be observed by reference to Fig. 3 and also to Fig. 4, that the eye member as a whole is slightly dished or concaved and that the eye l projects from the frame in such manner as to readily 75 engage the hook. The eye member is connected with the tab by carrying the material around the frame bar g, then through the space between the bar g and the cross-piece L, then under the cross-piece L and over 80 the frame bar g'. The two ends of the tab are connected with each other and with the pad. Experience has demonstrated that this form of eye and this manner of connecting it with the tab is most efficient as the eye 85 member can in this way be quickly attached to the tab without stitching and the teeth x so engage the tab that there is no danger of the fabric slipping on the frame. While this device is particularly useful when applied to wide leg-bands, it may also be used 90 in leg-bands of other kinds.

I claim as my invention:

1. An eye member of a hook-and-eye fastener, consisting of a frame having front and 95 rear frame bars connected by end bars which are in turn connected by a cross-piece formed with an eye, one of said longer frame bars being formed on its outer edge with teeth adapted to engage a fabric. 100

2. An eye member of a hook-and-eye fastening, comprising a dished or concaved frame, consisting of relatively long front and rear frame bars connected by relatively short cross-bars which are in turn connected by a 105 projecting eye, one of said longer frame bars being formed on its outer edge with a series of teeth adapted to engage a fabric.

In testimony whereof, I have hereunto 110 subscribed my name.
